UNITED STATES PATENT OFFICE.

CHARLES HARRINGTON PECK, OF PHILADELPHIA, PENNSYLVANIA.

STREET-TRAFFIC-SIGNALING DEVICE.

1,332,917.

Specification of Letters Patent. Patented Mar. 9, 1920.

Application filed April 19, 1915, Serial No. 22,475. Renewed December 3, 1919. Serial No. 342,268.

To all whom it may concern:

Be it known that I, CHARLES HARRINGTON PECK, of Philadelphia, in the State of Pennsylvania, have invented a new and useful 5 Improvement in Street-Traffic-Signaling Devices, of which the following is a description.

My invention relates to new and useful improvements in street traffic signaling devices, and has for its object to provide an exceedingly simple and effective device of this character, whereby a number of signaling arms or semaphores may be simultaneously operated to indicate to the traffic at 10 the corner of two cross streets or at two traffic lanes upon the same street which direction of travel is open to the traffic, and the direction or directions of travel which are closed to the traffic.

Another object of the invention is to provide in combination with the above referred to signaling arms or semaphores, colored 20 signaling spectacles carried by said signaling arms, and adapted to pass in front of a light, the latter being arranged at a point equi-distant from all of the arms and mounted upon the operating shaft, so as to turn therewith when the signals are being operated.

A further object of the invention is to provide in combination with the visual signals, means for giving an audible signal during the changing of the positions of the signal arms.

Still another object of the invention is to provide means for actuating the gears to which the signal arms are attached, whereby one or more of said signal arms may be operated.

A further object of the invention is to provide a waterproof attachment for the signaling devices, whereby the traffic officer may be protected or housed during inclement weather.

A still further object of the invention is to provide a pedestrian signal adapted to operate in conjunction with the main traffic signal, acting as a sunshade or umbrella to protect the traffic officer from the sun's rays 45 or from rain.

Another object of the invention is to provide a portable traffic signaling device, so that the same may be readily moved from place to place.

Still another object of the invention is to

provide a signaling device which may be placed upon a stand, so as to be set upon a street or to which may be secured suitable split brackets, so that the device may be attached to poles or posts, such as lamp 60 posts.

With these ends in view, this invention consists in the details of construction and combination of elements hereinafter set forth and then specifically designated by 65 the claims.

In order that those skilled in the art to which this invention appertains, may understand how to make and use the same, I will describe its construction in detail, referring by numerals to the accompanying drawings forming a part of this application, in which—

Figure 1, is a top or plan view of my improved street traffic signaling device, showing 75 portions of some of the arms broken away.

Fig. 2, is a section on the line A—B of Fig. 1.

Fig. 3, is a side elevation thereof.

Fig. 4, is a similar view at right angles to Fig. 3, showing the audible signal or gong.

Fig. 5, is a side elevation of one of the gong operating arms.

Fig. 6, is a side elevation of the signaling 85 device, showing the pedestrian signal and the curtains for forming the waterproof enclosure.

Fig. 7, is a fragmentary side elevation of the upright or standard illustrating the 90 means of operating the pedestrian signal.

Fig. 8, is a plan view on a reduced scale of the pedestrian signal, and

Fig. 9 is a section of the standard below 95 the gong showing the positions of the hammer actuating fingers.

In carrying out my invention as here embodied 2 represents an upright or supporting standard having its lower end screwed into a stand or base 3, whereby said upright 100 may be readily and quickly attached to or detached from said stand or base. The upright or standard 2 is provided at different points with threaded sockets 4, to which are detachably secured the split brackets or 105 clamps R by means of threaded projections 5, carried by one of the members of the split brackets or clamps. When these split brackets are used, the stand or base 3 is removed and the signaling device is attached to some 110

object such as a pole or post by means of said split brackets R. The upper end of the standard or upright 2 carries a head I, in the ears 6 of which are journaled the semaphore shafts 7. On the outer ends of said shafts are mounted the signal arms or semaphores A, B, C and D, and on the inner ends of these shafts are mounted the gears E, F, G and H. Within the upright or standard 2 is situated the operating shaft O journaled in the ball races P and Q, and to this operating shaft adjacent its lower end is secured a handle 8 projecting through a slot 9 in the standard or upright 2, said slot being of sufficient size to permit a limited vertical movement of the handle 8 as well as the rotating movement thereof.

Above the head I is situated a gear operating segment K arranged to rotate with the operating shaft O, but which is loosely mounted thereon, so that said shaft may slide through the segment K. The gear operating segment K meshes with the underside of the gear H, and above this segment upon the operating shaft is also mounted a selective gear operating segment J having two gear segment arms 10 and 11, either of which is adapted to mesh with the gear F. This selective gear operating segment J is secured to the operating shaft O so as to move vertically therewith.

Above the selective gear operating segment J is situated a gear operating segment L adapted to rotate with the operating shaft O, but having a loose or sliding connection therewith, whereby said shaft may be moved vertically without disengaging the segment L from its gears. Said gear operating segment L meshes with the upper sides of the gears E and G. The last named segment is provided with a lamp holding means or socket 12, in which is mounted the lamp M adapted to rotate with the segment L, and this lamp may be of one solid color, or it may have different colors, so as to correspond with the colored glasses or spectacles N carried by the signal arm. The lamp or light M is equi-distant from all of the signaling arms, so that the rays of light from said lamp passing through the different spectacles will be of the same intensity.

The signal arms all operate in unison, and are generally moved into and out of signal position in pairs, that is the diametrically opposite signal arms forming one pair move into signal position when the diametrically opposite signal arms forming the other pair move out of signal position, so that when one street is open to traffic, the other or cross street is closed to traffic.

When the operating handle 8 is raised, so that the arm 11 of the selective gear operating segment J is in mesh with the gear F, then the signal arms D and B will move out of signal position when the signal arms A

and C move into signal position, caused by moving the handle 8 from side to side or rotating the operating shaft O.

If for any desirable reason the traffic officer wishes one of the arms to remain stationary, while operating the other three arms, the handle 8 is lowered to a neutral position, at which time neither of the segment arms 10 and 11 will mesh with the gear F, so that the signal arm connected therewith will stand still, or if it is desired, that the signal arm B be moved to a signal position when the signal arm D moves out of signal position; then the handle 8 is moved still lower or until the segment arm 10 meshes with the gear F, thus reversing the movement of the signal arm B with relation to the signal arm D.

The head I and the different gears may be inclosed by a suitable casing S shown in Fig. 4.

In order that the traffic may be notified of a change in position of the signal arms, I provide a suitable audible signal device such as a gong 13 having a spring actuated hammer 14 adapted to be operated by suitable trip levers T provided with means such as a notch or notches 15 respectively adapted to engage with one of the fingers 25 of the hammer 14 for swinging the same against the action of its spring, and one of these fingers passes around each side of the standard 2 while the trip levers are pivoted to the signal arms as shown in Fig. 4. These trip levers are so arranged that when the signal arms to which they are attached are lowered or moved out of signal position the trip lever with a certain number of notches therein will operate the audible signal, while the other trip lever with a different number of notches therein will operate the audible signal when the arms are being raised or thrown into signal position, so that a person hearing two strokes of the gong will know that one street is being opened to traffic, while if but one stroke of the gong is heard, he will know that the other street is being opened to traffic.

In Fig. 6 I have shown a rotatable sleeve 16 mounted upon the upright or standard 2, and to this is attached a cover 17 similar to an umbrella, the outer surface having designations thereon to be used as a pedestrian signal. This cover may be used as an awning or parasol during bright sunny weather, or it may be used as an umbrella during rainy weather, thus protecting the traffic officer.

As a further protection to the traffic officer I provide waterproof walls or curtains 18 having openings therein covered with suitable transparent material 19, and these curtains may be attached to the cover or umbrella 17 in any suitable manner.

In order that the cover 17 will turn so as

to display the pedestrian signal in conjunction with the signal arms, I connect the sleeve 16 and the operating handle 8 by means of a link 20, so that as said handle 8 is moved from side to side the sleeve 16 will rotate therewith.

It is to be understood that any combination of different parts may be used, as for instance, the audible signal and the pedestrian signal may be eliminated as shown in Figs. 1, 2 and 3, the visible and audible signals may be used in conjunction as shown in Fig. 4, the pedestrian signal which also acts as a cover or inclosure may be used in conjunction with the visible signal or said pedestrian signal and the audible signal may be used in conjunction with the main visible signal. At night the signals are used in the same manner, but instead of the signal arms indicating the right of way, the colored spectacles will indicate to the traffic whether to stop or proceed, and since the lamp M is arranged to rotate, the signal spectacles upon the signal arms may be eliminated.

As will be readily understood, by the use of my improved signaling device embodying the visible and audible signal, it is impossible to give conflicting signals, since the audible signal is operated automatically, and in conjunction with the visible signals. Where a traffic officer uses a whistle for giving audible signals, and uses some kind of a visible signal, he might blow his whistle once, meaning that traffic is open upon one street and throw his visible signals, so that the traffic is open upon the cross streets, thus causing great confusion, since because of the conflicting signals both streets are open and the traffic upon one street continues to move, while the traffic upon the other street begins to move, but, as before stated, this is absolutely impossible with my improved signaling device, for when certain of the signal arms are raised, one audible signal is given, and when the other arms are raised, a different audible signal is given.

Of course I do not wish to be limited to the exact details of construction as here shown, as these may be varied within the limits of the appended claims without departing from the spirit of my invention.

Having thus fully described my invention, what I claim as new and useful, is—

1. A street traffic signaling device comprising an upright, a head carried thereby, shafts journaled in said head, arms mounted on the outer ends of said shafts, gears mounted on the inner ends of said shafts, an operating shaft, means for actuating the same, a gear operating segment loosely mounted on said last named shaft meshing with one of the gears, another gear operating segment loosely journaled on the operating shaft, and meshing with two other of

said gears which are diametrically opposite each other, and another gear operating segment comprising two segment arms secured to the operating shaft either of said segment arms adapted to mesh with another of said gears when the operating shaft is raised or lowered.

2. A street traffic signaling device comprising an upright, a head carried thereby, shaft journaled in said head, arms mounted on the outer ends of said shafts, gears mounted on the inner ends of said shafts, an operating shaft, means for actuating the same, a gear operating segment loosely mounted on said last named shaft meshing with one of the gears, another gear operating segment loosely journaled on the operating shaft, and meshing with two other of said gears which are diametrically opposite each other, another gear operating segment comprising two segment arms secured to the operating shaft, either of said segment arms adapted to mesh with another of said gears when the operating shaft is raised or lowered, a lamp carried by one of the gear operating segments and adapted to rotate therewith, and signaling spectacles carried by the signal arms.

3. A street traffic signaling device comprising an upright, a head carried thereby, shafts journaled in said head, arms mounted on the outer ends of said shafts, gears mounted on the inner ends of said shafts, an operating shaft, means for actuating the same, a gear operating segment loosely mounted on said last named shaft meshing with one of the gears, another gear operating segment loosely journaled on the operating shaft and meshing with two others of said gears which are diametrically opposite each other, another gear operating segment comprising two segment arms secured to the operating shaft, either of said segment arms adapted to mesh with another of said gears when the operating shaft is raised or lowered, a lamp carried by one of the gear operating segments and adapted to rotate therewith, signaling spectacles carried by the signal arms, and an audible signal actuated by the movements of the signal arms.

4. A street traffic signaling device comprising an upright, a head carried thereby, shafts journaled in said head, arms mounted on the outer ends of said shafts, gears mounted on the inner ends of said shafts, an operating shaft, means for actuating the same, a gear operating segment loosely mounted on said last named shaft meshing with one of the gears, another gear operating segment loosely journaled on the operating shaft and meshing with two other of said gears, another gear operating segment comprising two segment arms secured to the operating shaft, either of said segment arms adapted to mesh with another of said gears

when the operating shaft is raised or lowered, a lamp carried by one of the gear operating segments and adapted to rotate therewith, signaling spectacles carried by the signal arms, an audible signal, and means carried by certain of said signal arms for operating said audible signal.

5. A street traffic signaling device comprising an upright, a head carried thereby, 10 shafts journaled in said head, arms mounted on the outer ends of said shafts, gears mounted on the inner ends of said shafts, an operating shaft, means for actuating the same, a gear operating segment loosely 15 mounted on said last named shaft meshing with one of the gears, another gear operating segment loosely journaled on the operating shaft and meshing with two other of said gears which are diametrically opposite 20 each other, another gear operating segment comprising two segment arms secured to the operating shaft, either of said segment arms adapted to mesh with another of said gears when the operating shaft is raised or lowered, 25 a lamp carried by one of the gear operating segments and adapted to rotate therewith, and signaling spectacles carried by the signal arms.

6. A street traffic signaling device comprising a portable support, a plurality of 30 signal arms carried thereby arranged to operate in unison, means for operating each pair of signal arms in unison, a sleeve rotatably mounted upon the upright and adapted to rotate in conjunction with the raising and lowering of the signal arms, and a 35 pedestrian signal carried by said sleeve.

7. A street traffic signaling device comprising a portable support, a plurality of 40 signal arms carried thereby arranged to operate in unison, means for operating each pair of signal arms in unison, a sleeve rotatably mounted upon the upright and adapted to rotate in conjunction with the raising 45 and lowering of the signal arms, and a cover carried by said sleeve and adapted to rotate therewith, said cover acting as a pro-

tector and having indication marks thereon for use as a pedestrian signal.

8. A street traffic signaling device comprising a portable support, a plurality of 50 signal arms carried thereby arranged to operate in unison, means for operating each pair of signal arms in unison, a sleeve rotatably mounted on the upright and adapted 55 to rotate in conjunction with the raising and lowering of the signal arms, a cover carried by said sleeve and adapted to rotate therewith, said cover acting as a protector and having indication marks thereon 60 for use as a pedestrian signal, and curtains detachably secured to the cover, said curtains having openings therein covered with suitable transparent material.

9. A street traffic signaling device comprising in combination a set of signal arms, 65 means for moving said signal arms into and out of signal positions, a gong, and trip levers pivoted to certain of said signal arms, said trip levers being provided with means 70 for sounding different signals upon said gong.

10. A street traffic signaling device comprising an upright, a head carried thereby, 75 shafts journaled in said head, signal arms mounted on said shafts and adapted to be raised and lowered, a gong carried by the upright, a spring actuated hammer for sounding said gong and means carried by certain of the signal arms for actuating said 80 hammer.

11. A street traffic signaling device comprising an upright, a head carried thereby, 85 shafts journaled in said head, signal arms mounted on said shafts and adapted to be raised and lowered, a gong carried by the upright, a spring actuated hammer for sounding said gong and trip levers pivoted to certain of the signal arms and provided with means for actuating the hammer.
